UNITED STATES PATENT OFFICE.

ARTHUR T. CRANE, OF WATERBURY, CONNECTICUT, ASSIGNOR TO THE CHASE COMPANIES INC., OF WATERBURY, CONNECTICUT, A CORPORATION.

SPARK-PLUG.

1,367,303.

Specification of Letters Patent.

Patented Feb. 1, 1921.

Application filed February 25, 1920. Serial No. 361,176.

To all whom it may concern:

Be it known that I, ARTHUR T. CRANE, a citizen of the United States, residing at Waterbury, in the county of New Haven and State of Connecticut, have invented a new and useful Improvement in Spark-Plugs; and I do hereby declare the following, when taken in connection with the accompanying drawings and the characters of reference 10 marked thereon, to be a full, clear, and exact description of the same, and which said drawings constitute part of this application, and represent, in—

Figure 1, a view in side elevation of a 15 spark-plug embodying my invention.

Fig. 2, a view in central longitudinal section of the shell showing the installation therein of the locking-ring, as a condition precedent to the insertion of the insulator 20 or core.

Fig. 3, a view showing the introduction of the core into the housing after the installation of the locking-ring therein.

Fig. 4 a broken sectional view showing the 25 locking-ring as upset for permanently fastening the core in the shell.

Fig. 5, a detached plan view of the locking-ring before swaging.

Fig. 6, a view thereof in side elevation.

Fig. 7, a detached plan view of the sealing-gasket.

Fig. 8, an edge view thereof.

My invention relates to an improvement 35 in spark-plugs, the object being to provide simple and effective means for permanently securing their insulators or cores in their shells.

With these ends in view, my invention consists in a spark-plug having its insulator 40 or core permanently secured within its shell by means of a locking-ring having its inner edge expanded to form an anchoring-flange entering an undercut recess in the shell, and its projecting outer edge turned 45 inward over upon the core to hold the same in place.

My invention further consists in certain 50 details of construction as will be hereinafter described and pointed out in the claims; and in a method having certain steps as will be hereinafter described.

In carrying out my invention, as herein shown, I employ a shell or housing 2 having an under-cut annular recess 3 formed within 55 its upper edge for the reception of the cross-

sectionally wedge-shaped lower edge of a soft metal locking-ring 4 which is installed in the shell 2 prior to the introduction thereto of the insulator or core 5, the largest diameter of which adapts it to fit snugly 60 within the shell and also to pass through the locking-ring which is of uniform internal diameter, though its external diameter is enlarged toward its lower edge to fill the under-cut recess in the shell and so to adapt 65 the said edge to function as an anchor.

The locking-ring, is first installed in the recess 3 in the shell, as shown in Fig. 2, after which the core is inserted, as shown in Fig. 3. A conical sealing-gasket 6 is then set 70 within the open outer edge of the ring 4 so as to rest upon the beveled retaining-shoulder 7 of the core, after which the projecting outer edge of the ring is swaged, spun, or otherwise upset inward over the said gasket 75 so as to form an angle with its wedge-shaped inner portion, whereby the insulator or core is permanently held in place within the shell by its engagement at a point without the same.

In other respects than as described, the 80 spark-plug may be of any approved construction. As herein shown, it is provided with the usual gas-check gasket 8, a wire electrode 9, a ground-terminal 10, a terminal-cap 11, and a binding-nut 12, with none of which parts is my present invention concerned.

The locking-ring 4 may be produced and 85 installed in a variety of ways. As shown in Figs. 5 and 6, it consists of a tubular blank 13 having its inner edge beveled outwardly as at 14. Such a blank having been inserted into the shell, is subjected to pressure operations whereby its beveled lower edge is 90 turned outward into and upset in the undercut annular locking-recess 3, after which the core 5 is inserted into the shell through the ring. However, I do not limit myself to 95 making the ring of any particular form, so long as it is adapted in its form to be self-anchored in the shell and to project therefrom so as to be engaged with the insulator or core at a point outside of the shell.

I claim:

1. A spark-plug having a shell formed just within its upper end with an annular under-cut locking-recess, an insulator or core, and a deformable locking-ring adapted at its inner end to be anchored within the said 110

- recess and adapted at its outer end to project from the shell and to be engaged with the insulator or core for permanently holding the same in place within the shell.
5. 2. In a spark-plug, the combination with a shell formed just within its upper end with an annular under-cut locking-recess, of an insulator or core, and a deformable locking ring for permanently fastening the said core in the said shell, the said ring having its inner edge thickened to form an anchor within the said recess and its outer end adapted to be turned inward over the insulator or core at a point outside of the shell.
10. 3. In a spark-plug, the combination with a shell, formed within its upper edge with an annular under-cut recess, of an insulator or core adapted to be set within the said shell, and a locking-ring having its inner edge entered into the said recess in which it is upset and anchored and having its outer end engaged with the core or insulator at a point without the shell.
15. 4. In a spark-plug, the combination with a shell formed just within its upper end with an annular under-cut locking-recess, of

an insulator or core provided with a retaining-shoulder, a deformable locking-ring having its inner end anchored within the said recess and adapted to be turned inward over 30 the said shoulder at a point without the said shell, and a sealing-gasket applied to the said shoulder and interposed between the same and the projecting outer portion of the ring which is turned down upon it. 35

5. A method of assembling spark-plugs, consisting in installing and anchoring a locking-ring just within the upper end of a spark-plug shell, then introducing an insulator into the shell through the said ring, and 40 finally closing the ring upon a portion of the insulator exposed outside of the said shell for holding the insulator in place in the shell.

In testimony whereof, I have signed this 45 specification in the presence of two subscribing witnesses.

ARTHUR T. CRANE.
